US0D1108280S

(12) **United States Design Patent** (10) Patent No.: **US D1,108,280 S**
(45) Date of Patent: ** Jan. 6, 2026

(54) **SCOREBOARD**

(71) Applicant: **Krusader LLC**, Ladera Ranch, CA (US)

(72) Inventors: **Marko R. Zoretic**, Coto de Caza, CA (US); **Luka J. Zoretic**, Coto de Caza, CA (US); **Mateo M. Zoretic**, Coto de Caza, CA (US)

(73) Assignee: **Krusader LLC**, Ladera Ranch, CA (US)

(**) Term: **15 Years**

(21) Appl. No.: **29/952,312**

(22) Filed: **Jul. 15, 2024**

(51) LOC (15) Cl. **21-01**

(52) U.S. Cl.

USPC **D10/46.1**

CLAIM

The ornamental design for a scoreboard, as shown and described.

DESCRIPTION

FIG. 1 is an isometric view of a scoreboard showing the new design.

FIG. 2 is a front view of the scoreboard in FIG. 1.

FIG. 3 is a back view of the scoreboard in FIG. 1.

FIG. 4 is a top view of the scoreboard in FIG. 1.

FIG. 5 is a bottom view of the scoreboard in FIG. 1.

FIG. 6 is a left side view of the scoreboard in FIG. 1; and, FIG. 7 is a right side view of the scoreboard in FIG. 1.

The details shown in broken lines illustrate portions of the scoreboard that form no part of the claimed design.

1 Claim, 5 Drawing Sheets
